Primary Examiner—Alan P. Douglas**Assistant Examiner**—Robert M. Spear**[57]****CLAIM**

The ornamental design for adhereable dial for containers, as shown and described.

DESCRIPTION

FIG. 1 (7) is a perspective view of an adhesive dial for containers, showing my new design;

FIG. 2 is a top plan view thereof;

FIG. 3 is a bottom plan view thereof;

FIG. 4 is a cross-sectional view taken along lines 4—4 of FIG. 2; and,

FIG. 5 is an exploded view of my new design.
